BAILER

David Clinton Walker, Long Beach, Calif., assignor to Baash-Ross Tool Company, Los Angeles, Calif., a corporation of California

Application January 3, 1938, Serial No. 183,013

10 Claims. (Cl. 166—19)

This invention relates to a well tool and relates more particularly to a bailer for introducing or delivering material to a well. A general object of this invention is to provide a simple, practical and effective dump bailer for use in wells.

Another object of this invention is to provide a dump bailer for introducing acid, cement slurry, and other materials into a well that may be unloaded or operated to discharge its contents at any selected point in the well. The dump bailer provided by the present invention may be unloaded at the bottom of the well or at any higher point in the well and its unloading may be effected without engaging it against the bottom wall of the well.

Another object of this invention is to provide a bailer of the character mentioned that embodies a simple, dependable valve normally or initially held closed by the head pressure or the weight of the material contained in the bailer body and by the weight of certain elements of the bailer structure.

Another object of this invention is to provide a bailer of the character mentioned that may be easily and quickly unloaded at any selected point in the well by manipulation of the string or line carrying the bailer.

Another object of this invention is to provide a bailer of the character mentioned in which there is little or no possibility of the contents being accidentally discharged in the event that the lower element of the bailer strikes an obstruction or projection in the well when the bailer is being lowered in the well.

Another object of this invention is to provide a bailer of the character mentioned embodying novel and dependable latch means for latching the valve open to assure a full unloading of the material from the bailer body.

A further object of this invention is to provide a dump bailer of the character mentioned that is simple and inexpensive to manufacture and that is convenient to operate.

The various objects and features of my invention will be fully understood from the following detailed description of a typical preferred form and application of the invention, throughout which description reference is made to the accompanying drawings, in which:

Fig. 1 is a side elevation of the lower portion of the improved bailer provided by the present invention in a well with the parts in the normal positions. Fig. 2 is an enlarged longitudinal detailed sectional view of the intermediate portion of the bailer showing the valve closed. Fig. 3

is an enlarged longitudinal detailed sectional view of the lower end part of the bailer with the parts in the normal positions. Fig. 4 is a view similar to Fig. 1 showing the parts in the partially operated positions. Fig. 5 is a view similar to Fig. 2 showing the valve open and one of the latches actuated, and Fig. 6 is a fragmentary vertical sectional view showing the other latch actuated.

The bailer provided by the present invention includes, generally, a body 10 adapted to contain material to be discharged into a well W, a valve 11 for governing the discharge of the material from the body 10 and a control 12 for the valve 11 whereby the valve may be opened by movement or manipulation of the body 10 in the well W.

The bailer body 10 is an elongate hollow or tubular structure adapted to be lowered into the well W on a line or cable (not shown). The body 10 preferably includes an upper section 13 for containing the material to be delivered to the well and a lower section 14. The upper section 13 of the body 10 may be of any desired length to contain the required amount of material and the upper end of the section 13 is intended to be connected with the line for lowering the bailer into the well. The lower body section 14 is in the nature of a tubular extension on the lower end of the section 13. The sections 13 and 14 may be connected by a suitable coupling 15. A plug 16 is preferably provided for the lower end of the lower section 14. The plug 16 may be threaded in the lower portion of the section 14 and is provided with a central longitudinal opening 17. The body 10 is proportioned to readily pass through the well W or its casing.

The valve 11 is carried by the lower section 14 of the body 10 to normally retain or hold the material in the upper body section 13. The valve 11 includes a seat 18 on the interior of the lower body section 14. The seat 18 may be in the nature of a ring arranged in the upper portion of the section 14. The seat 18 may be secured in place in any suitable manner, for example, it may rest downwardly against a shoulder 19 on the interior of the section 14 and may be fixed to the section by welding 20. The seat 18 is preferably provided with a tapered surface 21 surrounding the upper portion of its opening 22. The surface 21 is annular and faces upwardly.

The valve 11 further includes a stem 23 arranged longitudinally through the lower body section 14 and a head on the stem 23 for cooperating with the seat 18. The stem 23 is slidable in the plug opening 17 and passes upwardly 55

through the opening 22 in the seat 18. A portion 24 of reduced diameter is preferably provided on the upper end of the stem 23 and provides the stem with an upwardly facing annular shoulder 25. The above-mentioned valve head includes a tapered or frusto-conical member 26 on the reduced stem portion 24 and a nut 27 threaded on the portion 24. The valve member 26 engaged downwardly against the shoulder 25 and the nut 27 cooperates with the upper end of the member to hold the member in place. The nut 27 may be tapered or conical and may be locked to the stem portion 24 by a pin 28. The valve member 26 is shaped and proportioned to fit downwardly against the surface 21 to completely close the opening 22 and thus trap or hold the material in the upper body section 13. When the bailer is to be employed to handle cement slurry and other non-corrosive materials the valve member 26 15 may be formed of steel or the like. When the bailer is to be employed to handle acid the valve member 26 is preferably formed of rubber, rubber composition or other material that is substantially unaffected by acid. The valve member 26 must have sufficient strength and rigidity to withstand the weight or head pressure of the column of fluid contained in the upper section 13 20 of the bailer body 10. It is to be observed that the valve member 26 sealing downwardly against the surface 21 is held in its closed position by the weight of the column of fluid in the body section 13.

A guide 29 may be provided in the lower body section 14 between the seat 18 and the plug 16 to assist in guiding the stem 23. The guide 29 may be welded to the interior of the section 14 and is provided with a central longitudinal opening which slidably passes the stem 23. A stop collar 30 may be secured to the stem 23 to cooperate with the under side of the guide 29 to limit the upward movement of the stem 23 relative to the body 10. One or more discharge ports 31 are provided in the wall of the body section 14. The ports 31 are located between the seat 18 and the guide 29 and in practice may be at or adjacent the upper side of the guide. The ports 31 are provided to discharge the acid, cement or material handled by the bailer and of course are controlled by the valve member 26 cooperating with the seat 18. A vent or drain port 32 may be provided in the plug 16 to maintain the interior of the body section 14 between the plug and the guide 19 in communication with the well.

The control 12 for the valve 11 is an important feature of the invention and provides for the opening of the valve and the discharge of the fluid from the bailer body 10 at any selected point in the well W. In accordance with the invention the stem 23 extends a substantial distance downwardly beyond the plug 16 and its lower end preferably has a bull nose or guide 33. The control 12 includes a tailpiece A on the projecting lower portion of the stem 23. The tailpiece A is in the nature of an anchor and includes longitudinally spaced sleeves 34 and 35 shiftable on the stem 23 and leaf springs 36 extending between and secured to the sleeves. The springs 36 are bowed outwardly to have frictional contact with the wall of the well W or the well casing to resist movement of the tailpiece A in the well.

Means is preferably provided to yieldingly resist relative movement between the stem 23 and the tailpiece A in one direction so that the engagement of the guide 33 with an obstruction

in the well will not produce substantial relative movement between the stem 23 and the tailpiece A. This means may consist of a helical spring 37 surrounding the stem 23 and arranged under compression between the upper side of the guide 33 and the lower side of the sleeve 35. The spring 37 serves to normally yieldingly hold the tailpiece A in a position where the upper end of the sleeve 34 is adjacent or in engagement with the lower end of the plug 16. It is to be understood that the tailpiece springs 36 cooperating with the wall of the well W offer such resistance to movement of the tailpiece A that the stem 23 may be intentionally moved upwardly with the body 10 relative to the tailpiece A to compress the spring 37 against the lower end of the lower tailpiece sleeve 35. A stop 38 may be provided on the stem 23 to cooperate with the underside of the sleeve 34 to limit upward movement of the stem 23 relative to the tailpiece A.

The control 12 is characterized by a latch 40 for latching the stem 23 and the parts carried thereby against downward movement relative to the tailpiece A following an upward movement of the stem relative to the tailpiece A. In the form of the invention illustrated in the drawings the latch 40 is carried by the stem 23 to cooperate with the sleeve 35 of the tailpiece A. A vertical slot 41 is provided in the stem 23 and a pin 42 passes transversely through the upper portion of the slot. The latch 40 is pivoted on the pin 42 and normally depends in the slot 41. A notch is formed in the lower outer corner of the latch 40 and provides the latch with a downwardly facing shoulder 43 and an outwardly facing shoulder 44. A plate 45 may be welded across the lower outer portion of the slot 41 and is engageable by the shoulder 44 to limit the outward pivoting of the latch 40. Spring means is provided to yieldingly urge the latch 40 outwardly. Aligned sockets 46 are provided in the opposing inner surfaces of the latch 40 and the slot 41 and a helical spring 47 is arranged under compression in the sockets 46 to urge the latch 40 outwardly.

The parts are proportioned and related so that the outer side of the latch 40 cooperates with the wall of the opening 35^a in the sleeve 35 when the member 26 is in sealing engagement with the surface 21. The sleeve opening 35^a is preferably of substantial length so that the latch 40 may move in the opening when there is limited relative longitudinal movement between the tailpiece A and the stem 23 when the bailer is run into the well. When the body 10 is moved upwardly with the parts of the bailer in the normal positions the stem 23 moves upwardly relative to the tailpiece A so that the latch 40 moves upwardly through the opening 35^a in the tailpiece sleeve 35. The latch 40 may move upwardly to a position where its shoulder 43 passes the upper end of the sleeve 35 and the spring 47 pivot the latch outwardly to a position such as illustrated in Fig. 6 of the drawings where the shoulder 43 cooperates with the upper side of the sleeve 35. The shoulder 43 cooperating with the upper end of the sleeve 35 holds the stem 23 against downward movement relative to the tailpiece A and subsequent downward movement of the body moves the seat 18 downwardly out of engagement with the valve member 26, thus opening the valve 11 to permit the discharge of material from the bailer.

The control 12 further includes a latch 48 for latching the stem 23 to the body 10 when the

valve seat 18 is in its open position with respect to the valve member 26 to assure the complete discharge of the material from the bailer. In the form of the invention illustrated in the drawings the latch 48 is carried by the stem 23 and cooperates with the plug 16. A longitudinal slot 50 is provided in the stem 23 and a pin 51 passes transversely through the upper portion of the slot 50. The latch 48 is pivoted on the pin 51 to depend in the slot 50. The lower outer corner of the latch 48 is notched to have a downwardly facing shoulder 52 and an outwardly facing shoulder 53. A plate 54 may be welded across the lower outer part of the slot 50. The plate 54 is engageable by the shoulder 53 to limit outward pivoting of the latch 48. Aligned sockets 55 are provided in the opposing surfaces of the latch 48 and the slot 50 and a spring 56 is arranged in the sockets 55 to yieldingly urge the latch 54 outwardly. When the valve member 26 is in its closed position in engagement with the seat 18 the latch 48 bears outwardly against the wall of the opening 17 in the plug 16 with its shoulder 52 some distance below the upper end of the plug. When the valve 11 is opened by upward movement of the body 10 followed by downward movement of the body 10, as described above, the downward movement of the body with respect to the tailpiece A and the stem 23 brings the upper end of the plug 16 below the shoulder 52. When this occurs the spring 56 moves the latch 48 outwardly so that the shoulder 52 cooperates with the upper end of the plug 16 to definitely prevent downward movement of the stem 23 relative to the body 10 so that the seat 18 and the valve member 26 are maintained in spaced relation.

It is believed that the operation of the improved dump bailer provided by this invention will be readily understood from the foregoing detailed description. The bailer may be assembled with the parts in the position illustrated in Figs. 1, 2 and 3 of the drawings and the material to be delivered into the well may be provided in the upper section 13 of the body 10. The bailer may be lowered or run into the well W on a line. It will be observed that the valve member 26 seals downwardly against the seat 18 to positively prevent the loss of the material from the bailer and to be held tightly closed by the weight of the column of material in the body section 13. The weight of the column of material in the section 13 and the pressure exerted by the spring 37 effectively resist opening of the valve member 26 in the event the guide 33 strikes a projection in the well when the bailer is being lowered in the bore. This action of the column of fluid and the spring 37 prevents accidental or premature unloading of the bailer. When the bailer has reached the selected position in the well the body 10 is raised or moved upwardly. The frictional contact of the springs 36 with the wall of the well W holds the tailpiece A against movement during upward shifting of the body 10 with the result that the stem 23 moves upwardly relative to the sleeve 35. This upward movement of the stem 23 brings the latch 40 to a position where its shoulder 43 latches into engagement with the upper end of the sleeve 35. Following the above described upward movement of the body 10 the body is moved downwardly or is allowed to settle. The springs 36 of the tailpiece A cooperating with the wall of the well W hold the tailpiece against movement and the latch 40 cooperating with the

sleeve 35 as just described holds the stem 23 against movement with the result that downward movement of the body effects downward movement of the seat 18 out of engagement with the valve member 26. This, of course, allows the material in the upper section 13 of the body 10 to discharge through the opening 22 and the ports 31 to flow into the well. The opening of the valve 11 is accompanied by latching of the stem 23 to the body 10. The above described downward movement of the body 10 relative to the tailpiece A and the stem 23 brings the upper end of the plug 16 to a position where the latch 48 pivots outwardly to have its shoulder 52 engage the upper end of the plug. The latch 48 engaging the upper end of the plug 16 definitely prevents upward movement of the body 10 relative to the stem 23 and downward movement of the stem 23 relative to the body 10 and accordingly holds the valve 11 fully opened. Thus the contents of the upper body section 13 are free to completely discharge into the well. Following the dumping or discharging of the bailer the bailer may be withdrawn from the well on its line.

From the above description of operation of the bailer it will be apparent that the bailer may be manipulated to discharge its contents at any selected point in the well. In the event it is desired to discharge the bailer immediately adjacent the bottom of the well bore the bailer may be merely lowered into the well to engage the guide 33 against the bottom wall of the well. When this occurs the stem 23 and the valve member 26 are held against further downward movement and continued downward movement of the bailer body 10 moves the seat 18 downwardly away from the valve member 26 to permit the discharge of the contents from the section 13. The stop 30 on the stem 23 is engageable by the guide 29 to limit the downward movement of the bailer body relative to the stem 23.

Having described only a typical preferred form and application of my invention, I do not wish to be limited or restricted to the specific details herein set forth, but wish to reserve to myself any variations or modifications that may appear to those skilled in the art or fall within the scope of the following claims.

Having described my invention, I claim:

1. A bailer for introducing material into a well comprising a body for containing the material, the body having an outlet for the material, a valve seating downwardly to close the outlet, and a control for the valve including a tailpiece frictionally cooperating with the wall of the well and shiftably connected with the valve, and latch means for connecting the valve and tailpiece to latch the valve against downward movement relative to the tailpiece whereby downward movement of the body relative to the tailpiece opens the valve.

2. A bailer for introducing material into a well comprising a body for containing the material and having an outlet, valve means for the outlet comprising a seat on the body and a valve cooperable with the seat, and a control comprising two elements, one a stem on the valve, the other a unit shiftable on the stem and having parts frictionally engaging the wall of the well to resist its movement, and latch means engaged by movement of the stem with the body in one direction to connect the stem and unit against relative movement in the other direction whereby

- subsequent movement of the body in the said other direction separates the seat and valve, the latch means including a shoulder on one element, and a pivoted latch on the other element for engaging the shoulder.
3. A bailer for introducing material into a well comprising a body for containing the material and having an outlet, valve means for the outlet comprising a seat on the body and a valve sealing downwardly against the seat, a stem on the valve, and a control comprising a unit shiftable on the stem and comprising parts frictionally engaging the wall of the well to resist its movement, and latch means engaged by upward movement of the stem with the body to connect the stem and the unit and prevent downward movement of the stem relative to the unit whereby the unit holds the stem against downward movement during subsequent downward movement of the body to move the seat downwardly away from the valve.
4. A bailer for introducing material into a well comprising a body for containing the material and having an outlet, valve means for the outlet comprising a seat on the body and a valve sealing downwardly on the seat, a stem on the valve and a control comprising a tailpiece shiftable on the stem and including parts frictionally engaging the wall of the well to resist its movement, and latch means operable by upward movement of the stem with the body to connect the stem with the tail-piece whereby the tail-piece holds the valve against downward movement during subsequent downward movement of the seat with the body.
5. A bailer for introducing material into a well comprising a body for containing the material and having an outlet, valve means for the outlet comprising a seat on the body and a valve sealing downwardly on the seat, a stem on the valve and a control comprising a tailpiece shiftable on the stem and including parts frictionally engaging the wall of the well to resist its movement, latch means operable by upward movement of the stem with the body to connect the stem with the tailpiece whereby the tail-piece holds the valve against downward movement during subsequent downward movement of the seat with the body and latch means preventing subsequent downward movement of the stem relative to the body to prevent closing of the valve.
6. A bailer for introducing material into a well comprising a body for containing the material and having an outlet, valve means for the outlet comprising a seat on the body and a valve sealing downwardly against the seat, a stem on the valve, a tailpiece shiftable on the stem and including springs cooperable with the wall of the well to resist its movement, and a latch on the stem cooperable with the tailpiece to latch the stem against downward movement relative to the tailpiece whereby subsequent downward movement of the body moves the seat down away from the valve.
7. A bailer for introducing material into a well comprising a body for containing the material and having an outlet, valve means for the outlet comprising a seat on the body and a valve sealing downwardly against the seat, a stem on the valve, a tailpiece shiftable on the stem and including springs cooperable with the wall of the well to resist its movement, means yieldingly resisting upward movement of the stem relative to the tailpiece, and a latch on the stem cooperable with the tailpiece to latch the stem against downward movement relative to the tailpiece whereby subsequent downward movement of the body moves the seat down away from the valve.
8. A bailer for introducing material into a well comprising a body for containing the material and having an outlet, valve means for the outlet comprising a seat on the body and a valve sealing downwardly against the seat, a stem on the valve, a tailpiece shiftable on the stem and including springs cooperable with the wall of the well to resist its movement, a latch on the stem cooperable with the tailpiece to latch the stem against downward movement relative to the tailpiece whereby subsequent downward movement of the body moves the seat down away from the valve, and a latch on the stem cooperable with the body to prevent downward movement of the stem relative to the body.
9. A bailer for introducing material into a well comprising a body for containing the material and having an outlet, valve means for the outlet comprising a seat on the body and a valve sealing downwardly against the seat, a stem on the valve, a tailpiece shiftable on the stem and including springs cooperable with the wall of the well to resist its movement, a guide member on the stem, a spring between the tailpiece and the guide member resisting upward movement of the stem, and a latch on the stem cooperable with the tailpiece to latch the stem against downward movement relative to the tailpiece whereby subsequent downward movement of the body moves the seat away from the valve.
10. A bailer for introducing material into a well comprising a body for containing the material and having an outlet, valve means for the outlet comprising a seat on the body and a valve sealing downwardly against the seat, a stem on the valve, a tailpiece shiftable on the stem and including springs cooperable with the wall of the well to resist its movement, a guide member on the stem, a spring between the tailpiece and the guide member resisting upward movement of the stem, the weight of the material in the body and said spring preventing opening of the valve in the event the guide encounters an object in the well, and latch means for latching the stem against downward movement relative to the tailpiece whereby subsequent downward movement of the body effects movement of the seat away from the valve.

DAVID CLINTON WALKER.
